Atty's.

UNITED STATES PATENT OFFICE.

HARRY S. HART, OF CHICAGO, ILLINOIS.

DRAFT MECHANISM.

Application filed October 9, 1922. Serial No. 593,219.

To all whom it may concern:

Be it known that I, HARRY S. HART, a citizen of the United States, residing at Chicago, in the county of Cook and State of Illinois, have invented certain new and useful Improvements in Draft Mechanism, of which the following is a specification.

This invention relates to a new and improved draft mechanism for railway cars and more specifically to a construction of the supporting means for coupler shanks in said mechanism.

In earlier forms of striking castings, a separate detachable carry iron was provided since the rear of the coupler shank carried large shoulders and it was not practical therefore to introduce the shank axially through the opening in the striking casting.

With such constructions it was possible to replace the carry iron when it became worn without the necessity for replacing the entire striking casting. This separable construction was undesirable, however, for the reason that the carry iron retaining members were subject to wear, breakage or displacement with consequent failure to retain the carry iron in place. Loss of the carry iron rendered it impossible to couple the car since in order to couple properly the coupler head must be maintained within relatively narrow limits as to vertical height.

While the integral striking casting and carry iron obviates the difficulties incident to possible loss of the carry iron, it presents other difficulties in that the carry iron is subject to wear. When this wear becomes so great that the coupler head hangs lower than the proper coupling height, it then becomes necessary to replace the entire striking casting and carry iron. This replacement is expensive and requires that the car be placed out of service for a relatively long period.

In order to secure the advantages of both the integral and separable carry iron structures without the disadvantages of either, it has been proposed to provide wear plates carried by the integral carry iron, the wear plates being removable when they become worn to such an extent as to lower the coupler head below the proper height. A construction of this character is shown in the patent to Neikirk, No. 1,419,508, granted June 13, 1922.

In the Neikirk construction the wear plate is housed in the carry iron and the carry iron

becomes subject to wear when the wear plate has been worn down to the level of the embracing carry iron portions. Further, the carry iron, since it embraces the wear plate, is subject to accidental blows which may cause breakage with consequent necessity for replacement of the entire striking iron and carry iron casting.

It is an object of the present invention to provide a carry iron and associated wear plates so related that the wear plate embraces a portion of the carry iron.

It is an additional object to provide a construction of this character in which the wear plate is supported from the carry iron by an automatic centering rocker and in which the wear plate embraces a portion of both the rocker and the carry iron.

It is a further object to provide a construction in which the rocker embraces a portion of the carry iron and is in turn embraced by the wear plate.

Other and further objects will appear as the description proceeds.

I have illustrated a preferred embodiment of my invention in the accompanying drawings, in which—

Figure 1 is a face view of my improved construction;

Figure 2 is a plan view partly in section taken on line 2—2 of Figure 1; and

Figure 3 is a vertical section taken on line 3—3 of Figure 1.

Referring to the drawings, the striking casting 5 has the carry iron 6 formed integrally therewith. The striking casting 5 is secured to the end sill by rivets 8. The lateral arms of the casting are secured to the center sills 9 by rivets 10. The draft lugs 11 are secured to the center sills 9 by the rivets 12. The carry iron 6 is provided with the upwardly extending flange 13. The upper face of the carry iron upon either side of the flange is formed with the arcuate depressions 14 adapted to receive the rounded bearing surfaces 15 of the centering rockers 16.

The wear plate 17 is carried upon the upper face of the rockers 16 and is provided with the upwardly extending lugs 18 embracing the coupler shank 19 which has been indicated in broken lines in Figure 1.

As best seen in Figure 3, the wear plate 17 is provided with the downwardly extending flanges 20 which embrace the upper por-

tions of the rockers 16 and also embrace the upper portion of the carry iron flange 13.

In this form of construction a portion of the carry iron is housed by the rockers and 5 portions of both rockers and carry iron are housed by the wear plate. The readily removable parts, the rockers and wear plates thus protect the integral carry iron from wear.

10 While one preferred form of my invention has been illustrated, I contemplate such modifications as come within the scope of the appended claims.

I claim:

15 1. In a railway car, a carry iron having a flange thereon, a wear plate, and means supporting the wear plate, said means housing the flange on the carry iron.

20 2. In a railway car, an integral striking casting and carry iron, an upwardly extending flange on the carry iron, a wear plate, and means housing the carry iron flange and

supporting the wear plate, the wear plate housing a portion of the supporting means.

3. In a railway car, an integral striking 25 casting and carry iron, automatic centering means comprising a rocker and a wear plate, the rocker embracing a portion of the carry iron.

4. In a railway car, an integral striking 30 casting and carry iron, automatic centering means comprising a rocker and a wear plate, the rocker embracing a portion of the carry iron, and the wear plate embracing the rocker.

35 5. In a railway car, an integral striking casting and carry iron, automatic centering means comprising a rocker and a wear plate, a flange on the carry iron, the rocker embracing said flange, and the wear plate embracing the rocker and flange.

Signed at Chicago, Illinois, this 4th day of October, 1922.

HARRY S. HART.
